UNITED STATES PATENT OFFICE

PASQUALE MANCUSI, OF NEW YORK, N. Y., AND VINCENZO DI SIBIO, OF GLASSBORO, NEW JERSEY, ASSIGNEES TO PURSMOKE PIPE COMPANY, INC., OF NEW YORK, N. Y., A COMPANY OF DELAWARE

TOBACCO PIPE

Application filed June 30, 1930. Serial No. 464,905.

Our invention relates to new and useful improvements in a tobacco pipe and has for one of its objects to provide an exceedingly simple and effective device of this character which will give a sweet, cool, dry smoke.

Another object of the invention is to so arrange the structural details that accumulated moisture or saliva will be prevented from re-entering the tobacco bowl or the draft passage through the stem.

A further object of the invention is to generally improve the construction of pipes of this character to not only prevent the return of moisture to the tobacco bowl or the stem, but which, to some extent at least, will separate some of the deleterious substances and prevent the same from passing into the mouth of the user.

With these ends in view, this invention consists in the details of construction and combination of elements hereinafter set forth and then specifically designated by the claims.

In order that those skilled in the art to which this invention appertains may understand how to use and make the same, we will describe its construction in detail, referring by numerals to the accompanying drawings forming a part of this application, in which:

Fig. 1 is a longitudinal sectional view of a tobacco pipe embodying one form of our invention with a part of the mouth piece left in elevation.

Fig. 2 is a similar view of another form of the invention.

Fig. 3 is also a similar view of the modification of Fig. 2.

Fig. 4 is also a sectional elevation of another form of the invention.

Fig. 5 is a similar view of a modification of Fig. 4.

Figs. 6 and 7 are views partly in section and partly in elevation of a form similar to those shown in Figs. 4 and 5 but embodying features for the same general characteristics as those illustrated in Figs. 3 and 2 respectively.

Fig. 8 is a view of a pipe partly in section and partly in elevation illustrating a further modification of our invention.

Fig. 9 is a similar view of a further modification embodying features shown in Figs. 1 and 2.

In carrying out the invention as embodied in Fig. 1, 10 represents the pipe bowl which is carried by the stem 11 and said stem has a bore 12, the outer end of which may receive the mouth piece 13 while the inner end has an outlet 14 leading to the bottom of the pipe bowl. The outlet 14 is normally closed by a cap or closure 15 having threaded engagement with the lower ends of the pipe bowl as indicated at 16 and said closure is provided with a collar 17 of smaller circumference than the closure so as to be inside of the rim on which the threads are formed and this collar is adapted to register with the annular recess 18 surrounding the outlet 14 and in which may be mounted a gasket or packing ring 19 to be compressed by the collar 17 when the closure is mounted on the pipe and thereby prevent any possibility of leakage.

In the bowl 10 is formed the tobacco receiving chamber 20, the lower end of which terminates short of the bore 12 but communicates with the latter through an opening 21 in which is mounted a tube 22 so that the lower end thereof projects into the bore 12 with the lower terminal of said tube spaced from all the walls of the pipe or more particularly all the walls of the bore 12 into which the tube projects and therefore no matter what position the pipe may assume, the liquid accumulations in the bore 12 will not pass through said tube into the tobacco receiving chamber.

A tube 23 is also mounted in the draft passageway 24 through the mouth piece with an end of said tube projecting some distance beyond the inner end of the mouth piece and into the bore 12 so that the terminal of said tube within the bore 12 is spaced from all the walls of the pipe and any accumulations in the bore 12 will not enter the tube and therefore cannot pass into the mouth of the smoker.

During the smoking of the pipe, smoke will be drawn into the bore 12 and will remain therein during the space of time between puffs so that it may be cooled off and some of the moisture therein will probably condense

so that after the very first puff, the smoke should be dryer and cooler.

To carry out the same ideas and objects in a slightly different form, we have illustrated in Figs. 2 and 3 a pipe including a bowl 25 having a chamber 26 therein which in Fig. 3 is used to actually receive the tobacco while in Fig. 2 this chamber is only to receive a removable tobacco holding bowl 27, the lower end of which is preferably smaller than the chamber 26 so as to leave a space between the contiguous walls while at the upper end of the bowl 27 are external threads which engage internal threads on the inside of the pipe bowl 25 as shown at 28 and further, the upper edge of the bowl 27 is provided with a flange 29 to overlie or partially surround the edge of the pipe bowl proper. Communication between the interior of the bowl 27 and the chamber 26 is had through holes 30 in the bowl 27.

With the main pipe bowl is formed the stem 31 having a bore 32 lengthwise thereof in the outer end of which is mounted the mouth piece 33 and said bore 32 at or adjacent its inner end is in communication with the chamber 26 in the bowl through a hole 34.

In the hole 34 is mounted a tube 35 having its lower end projecting some distance into the bore 32 whereby the lower terminus of said tube is spaced from all the walls of the pipe and more particularly the walls of the bore 32 to prevent passage of accumulated moisture or foreign matter in the bore from entering the pipe bowl.

The tube 36 is mounted in the draft passageway 37 of the mouth piece in such manner that the outer end of said tube projects some distance from the mouth piece and when in use extends a considerable distance into the bore 32 so that the free terminus thereof is spaced from all of the walls of the pipe to prevent the accumulations within the bore 32 from passing into the tube and thence through the mouth piece into the smoker's mouth.

In Figs. 4 to 7 inclusive we have shown a tobacco pipe including a bowl 38, an angular stem 39, and a mouth piece 40. In each instance, the stem has a bore 41 in the outer end of which is mounted the mouth piece and the latter is provided with a draft passageway 42.

In the inner end of the draft passageway is mounted a tube 43 which projects a considerable distance into the bore 41 so that the inner terminus of the tube 43 is spaced from all the walls of the pipe to prevent the passage of accumulations from within the bore 41 to the mouth piece.

In Figs. 4 and 5 the pipe bowl has a tobacco receiving chamber 44 with a reduced opening 45 leading to an intermediate chamber 46, the latter being so fashioned that what might be

termed a lower corner communicates with the bore 41 near the latter's lower end.

In Fig. 4, a plug 47 is socketed in the reduced opening 45 while in Fig. 5 the plug 47a is threaded into the reduced opening 45 and the upper portions of these plugs are so formed that they produce the lower curved part of the tobacco bowl or chamber and blend into the side walls of the tobacco chamber 44.

Each plug has a hole through it in which is mounted a tube 48 so that the lower end projects into the intermediate chamber 46 a sufficient distance to space the lower terminus of the tube over all the walls of the pipe and prevent the accumulations in the intermediate chamber or the bore from passing into the tobacco chamber.

In Fig. 6 the chamber 49 in the bowl is the tobacco chamber and said chamber communicates with the bore 41 through an opening 50 in which is mounted a tube 51 having its inner end extending some distance into the bore 41 so that the terminus of said tube is spaced from all of the walls of the pipe.

The same general principles are carried out in Fig. 7 with the exception that the chamber 52 receives the tobacco bowl 53 having threaded engagement at its upper end with the upper end of the pipe bowl as indicated at 54 and said tobacco bowl is provided with a flange or rim 55 to surround or partially cover the upper edge of the pipe bowl. The tobacco bowl is shorter than the chamber 52 and the lower end of said tobacco bowl is preferably of less diameter than the inside of the pipe bowl so as to leave a space for the passage of the smoke laden air through the pipe and the interior of the tobacco bowl communicates with the chamber 52 through openings 56 in the bottom of the tobacco bowl.

The chamber 52 is in communication with the bore 41 through a hole 57 in which is mounted a tube 58 having its lower end extending into the bore 41 a considerable distance whereby the lower terminus of said tube is spaced from all the walls of the pipe.

In Fig. 8, we have shown a further modification of our invention by means of which a number of independent chambers are provided, but of course all are in communication so that the smoke that can travel from the bowl to the mouth piece is compelled to take a circuitous route and will be delayed in its final passage from the mouth piece and therefore will be cool and fairly dry. In this form of the invention, 59 represents a pipe bowl having a tobacco chamber 60 and said bowl is carried by the stem 61, which, while it may be of any length, is preferably short as shown and has a bore 62 in communication with the tobacco chamber 60 through a hole 63 and if found desirable, a tube 64 may be placed in said hole with the end of the tube extending some distance into the bore 62 whereby

the lower terminus of said tube will be spaced from all the walls of the pipe.

To the stem 61 is connected the stem extension 65 composed of one or more extension stem elements 66, each element having a bore 67 extending lengthwise from one end to a point short of the passage end and through the balance of said extension stem element is formed a hole 68 considerably smaller than the bore 67 and in this hole is mounted a tube 69, one end of which projects beyond the end of the element while the other end projects into the bore 67 and these ends extend a sufficient distance to space the terminus of the tubes from all of the surrounding walls of the pipe.

Each element is also provided with a plug 70 at the end carrying the tube 69 and said plug is to be socketed in the bore 62 of the regular pipe stem or in the bore of another similar extension element and while for convenience of illustration, I have shown said plugs as being merely slid into the bores of the coacting parts, it will be obvious that they can be provided with threads, bayonet joints or other suitable attaching means.

As will be obvious by reference to the drawings, the element which is connected with the pipe stem has one end of its tube projecting into the bore of the pipe stem and if there is a second or more elements, then the tube or tubes of said other element or elements will project into the bore of an adjacent element while the mouth piece 71 will project into the bore of the outermost extension stem element.

The mouth piece 71 has a draft passageway 72 and in the inner end of this is mounted a tube 73 having its outer end projecting some distance from the inner end of the mouth piece and into the bore of one of the stem extension elements so that the outer terminus of said tube is spaced from the walls of the pipe.

When the accumulations become so great within the bores of any of the parts that there is likelihood of the same entering one of the tubes, the parts may be readily separated and easily cleaned.

In Fig. 9 we have illustrated a slight modification of the structure shown in Fig. 1 wherein the pipe bowl 74 is carried by a stem 75 and said bowl has a chamber 76 to receive the tobacco receiving bowl 77 so fashioned that the lower part thereof is spaced from the walls of the pipe bowl but may be fastened in the upper end of said pipe bowl as by threads 78.

The tobacco receiving bowl is preferably provided with a flange 79 to partially surround or cover the upper edge of the pipe bowl and has holes 80 in its lower end to form communications between the inside of the tobacco receiving bowl and the chamber

In the lower part of the pipe bowl is formed an outlet 81 which is separated from the chamber 76 but is in communication therewith through a hole 82 wherein may be mounted a tube 83 having its lower end projecting into the outlet a considerable distance so that the lower terminus is spaced from the walls of the pipe. The outlet 81 is in communication through a reciprocated passageway 84 with the bore 85 in the stem. In the outer end of the stem is mounted a mouth piece 86 provided with a draft passageway 87 in the inner end of which is mounted a tube 88 having a portion extending away from the mouth piece and projecting a considerable distance into the bore 85 of the pipe stem so that the inner terminus of said tube is spaced from all the walls of the pipe to prevent accumulations in the bore 85 from passing into the tube and thence into the mouth piece through the smoker's mouth.

The outlet 81 is normally closed by a cap or closure 89 which cap includes an internally threaded flange or rim 90 for engagement with the externally threaded lower portion 90 of the pipe bowl and within said cap or closure is formed the collar 91 for registration with the annular groove 92 in which is contained a compressible washer or packing 93 to make a tight joint.

Of course we do not wish to be limited to the exact details of construction as herein shown, as these may be varied within the limits of the appended claims without departing from the spirit of our invention.

Having thus fully described our invention, what we claim as new and useful is:

1. A tobacco pipe including a bowl having a tobacco receiving chamber, a stem having a bore, a mouth piece mounted in said stem and provided with a draft passageway, a tube forming a communication between the interior of the bowl and the bore of the stem and another tube mounted in the draft passageway of the mouth piece, both of said stems having ends projecting considerable distances into the stem bore whereby the extreme ends of said tubes within the stem bore are spaced from all the walls thereof.

2. A tobacco pipe including a bowl having a chamber therein, a stem connected with the bowl and having a bore therein extending to a point below the chamber in the bowl and spaced from said chamber, said bore terminating in an outlet at the bottom of the pipe, a tube mounted in the bowl and forming a communication between the bowl chamber and the pipe stem with the end of said tube projecting a considerable distance into the stem bore so that its lower terminus is spaced from all the walls of the pipe, a closure removably mounted on the bottom of the pipe bowl for normally closing the outlet, a collar formed with said closure for registration with an annular groove formed in the bottom

- of the pipe about the outlet, a washer within said groove to be engaged by the collar, a mouth piece carried by the stem and having a draft passageway therethrough, a tube mounted in the inner end of the draft passageway with the outer end of said tube projecting a considerable distance into the stem bore whereby the terminus within the stem bore is spaced from all the walls of the pipe.
3. A tobacco pipe comprising a bowl having openings leading inward from opposite ends but terminating short of each other to produce a separating partition between them, said openings constituting a tobacco receiving chamber and an outlet and said partition having a hole forming a communication between the chamber and outlet, means to normally close the lower end of said outlet, a stem formed with the bowl and having a bore therein, an opening smaller than said bore forming a communication between said bore and the outlet, a tube mounted in the hole at the bottom of the chamber and extending a considerable distance into the outlet, a mouth piece mounted in the stem, a tube mounted in the draft passageway of the stem and having an end extending a considerable distance into the stem bore, and a tobacco bowl removably mounted in the chamber of the pipe bowl.
4. A tobacco pipe comprising a bowl having a chamber at its upper end and another chamber below the first mentioned one in communication therewith through a reduced opening, a stem connected with the bowl and provided with a bore having its inner end in communication with the second named chamber in the bowl, a plug mounted in the reduced opening and having a hole therethrough, a tube mounted in the hole in the plug and having its lower end extending a considerable distance into the lower chamber in the bowl whereby the lower terminus of said tube is spaced from all the walls of the pipe, a mouth piece mounted in the outer end of the stem and having a draft opening thereto, and a tube mounted in the inner end of the draft opening with an end of said tube projecting a considerable distance into the bore of the stem whereby the terminus of said tube within the stem bore is spaced from all the walls of the stem pipe.
5. A tobacco pipe comprising a bowl and stem, said stem having a bore therein and said bowl having a tobacco chamber and a secondary chamber communicating with the tobacco chamber and the stem bore, a plug slidably mounted in the lower end of the tobacco chamber so as to form the bottom wall thereof and the top wall of the secondary chamber, a tube passing through said plug and having its lower end projecting below the bottom of said plug and extending a considerable distance into the secondary chamber, a mouth piece having a draft opening, and a tube in

the inner end of said draft opening and projecting a considerable distance into the stem bore.

6. A tobacco pipe comprising a bowl and stem, said stem having a bore therein and said bowl having a tobacco chamber and a secondary chamber communicating with the tobacco chamber and the stem bore, a plug having threaded connection with the bowl at the lower end of the tobacco chamber so as to form the bottom wall of said tobacco chamber and the top wall of the secondary chamber, a tube mounted in said plug and passing entirely therethrough with the lower end extending a considerable distance away from said plug into the secondary chamber, a mouth piece carried by the pipe stem and having a draft passageway therethrough and a tube mounted in the inner end of said draft passageway and extending a considerable distance into the stem bore.

7. A pipe comprising a bowl having a chamber therein, an angular stem formed with said bowl and having a bore therein, the chamber in the bowl and the stem bore being in communication through a hole, a tube mounted in said hole with its lower end projecting into the stem bore, a mouth piece carried by the stem and having a draft passageway therethrough, a tube mounted in the inner end of said draft passageway and projecting a considerable distance into the stem bore.

8. A tobacco pipe including a bowl having a tobacco receiving opening, a stem having a bore, a mouth piece mounted in said stem and provided with a draft passageway, a tube mounted in the bowl and forming a communication between the tobacco receiving chamber and the bore, said tube projecting downwardly from the chamber into the bore, and another tube fitted in the draft passageway of the mouthpiece and projecting into the same bore as the first mentioned tube so as to project in a general downward direction from the mouth piece when the pipe is in use.

In testimony whereof, we have hereunto affixed our signatures.

VINCENZO DI SIBIO.
PASQUALE MANCUSI.
